UNITED STATES PATENT OFFICE.

OWEN POST ARNOLD, OF NEW BRITAIN, CONNECTICUT, ASSIGNOR TO THE RUSSELL & ERWIN MANUFACTURING COMPANY, OF SAME PLACE.

DESIGN FOR A LOCK-CASE.

SPECIFICATION forming part of Design No. 31,583, dated October 3, 1899.

Application filed July 27, 1899. Serial No. 725,325. Term of patent 14 years.

To all whom it may concern:

Be it known that I, OWEN POST ARNOLD, a citizen of the United States, residing in New Britain, in the county of Hartford and State of Connecticut, have invented and produced a new and original Design for a Pin-Tumbler Lock Case, of which the following is a specification, reference being had to the accompanying drawings, in which—

- Figure 1 is a rear perspective view of a lock-case, showing my design. Fig. 2 is a front elevation of the same, and Fig. 3 is a transverse section of the same on a plane a little to the rear of the front flange or face.
- A is the face or front flange, having the beveled edge 4, with round orifice 5 and annular rabbet 6. Just back of the front the case-body 12 is key-shaped in cross-section, as shown in Fig. 3, the orifice 5 extending the entire length of the case. The rear end of the case is cylindrical, with a ribbed and

grooved periphery 7, with longitudinal V-shaped grooves 8, while a shallow groove 9 extends along the top of the cylindrical portion and top of the key-shaped body portion, 25 as shown in Fig. 1. The cylindrical portion above the orifice 5 is provided with two longitudinal orifices 10 in the form of a modified triangle in cross-section, the web 11 between the said two orifices being substantially a 30 continuation of or in alignment with the web of the key-shaped body portion 12, all as shown.

Having described my invention, what I claim as new, and desire to secure by Letters 35 Patent, is—

The design for a lock-case as herein shown and described.

OWEN POST ARNOLD.
